UNITED STATES PATENT OFFICE

ROBERT BIENAIMÉ, OF PARIS, FRANCE

LOCK

Application filed July 19, 1930, Serial No. 469,105, and in Belgium August 2, 1929.

The present invention relates to locks and, more particularly, to those of the type adapted to be used on automobiles and like structures submitted to shock and vibration.

5 One of the objects of the invention is to provide a form of lock in which any wear of the working parts is automatically corrected and compensated.

Other objects will appear in the course of 10 the detailed description now to be given with reference to the accompanying drawings, in which:

Fig. 1 is an elevation, partially in section of one illustrative embodiment of the invention;

Fig. 2 is a section taken on line 2—2 of Fig. 1;

Fig. 3 is a section taken on line 3—3 of Fig. 1;

20 Fig. 4 shows, in elevation and in partial section, a variant of the structure represented in Figs. 1 to 3;

Fig. 5 represents a second modification; and

25 Fig. 6, a third variant.

Referring to Figs. 1 to 3 of the drawings, there is shown a male assembly composed of a bolt *a* carrying a roller *a*¹ and having a body portion of rectangular section except 30 where it engages with the female portion of the lock, this engaging portion having a trapezoidal section (Fig. 3) and including a first inclined surface *a*² sloping backward, downward, and away from the door frame, 35 and a second inclined surface *a*⁴ sloping backward and downward, but being formed of generatrices lying parallel to the door frame (or even sloping slightly towards the latter),—hooks *a*⁵ mounted on a yoke *a*⁶ forming an abutment for bolt *a*,—spring *e* attached to pin *e*¹ rigidly mounted on casing *d* supporting the male assembly,—a pivoted hand lever *c* operable to bear against roller *a*¹ to retract bolt *a*,—a spring *f* coupled to lever

40 *c* at *f*¹ and engaging with one of hooks *a*⁵,—and a latch *g*, whose use is optional, operative to lock lever *c* in position.

The above-described male assembly coacts with a female assembly composed of a shell *h* formed and dimensioned so that its upper and

lower parallel edges *b*² and *b*³ (Fig. 3) lie clear of bolt *a*, while an inclined surface *b*¹ contacts with surface *a*⁴ of the latter. Shell *h* is provided with a reentrant protruding portion formed to present (1) a sloping portion *h*¹ over which the free end of bolt *a* rides when the door is closed, and (2) an extension *h*² which contacts firmly with surface *i*¹ of a recess *i* forming part of casing *d*.

55 The lock operates as follows:

Casing *d* and shell *h* being mounted on the inside of the door and on the door-frame respectively, when the door is closed, the free end of bolt *a* contacts with surface *h*¹ and is forced inward, but as soon as closure is complete springs *e* and *f* move bolt *a* gradually to the left, further and further into shell *h*. The male and female assemblies are thus held firmly together against movement in any direction, and the combination of sloping surface *a*², and springs *e* and *f* compensate for wear of the surface *b*¹. Inclined surface *a*⁴ acts as a safety device to prevent bolt *a* from escaping surface *b*¹ when the lock has been incompletely closed and a pressure is exerted to open the door. As surface *a*⁴ does not slope relatively to the direction of displacement of bolt *a*, said bolt does not tend to get out of engagement with surface *b*¹ as would happen if the free end of the bolt ended with the sloping surface *a*².

80 Obviously, surface *h*² may be arranged to rest on the inferior portion of recess *i* and surfaces *b*¹ and *a*², *a*⁴ inclined in the opposite direction. Such an arrangement has, however the disadvantage of throwing the weight of the door on the bolt.

85 In the variant shown in Fig. 4, bolt *a* is made of rectangular cross-section throughout and, instead of providing inclined surfaces *a*², *a*⁴, *b*¹, as shown in Figs. 2 and 3, the axis of bolt is inclined as shown. In the construction shown in Fig. 4 the recess in shell *h* is provided with surfaces correspondingly in-

clined to the bolt *a* for engaging with the latter in the usual way. It will thus be seen that, as bolt *a* wears, springs (not shown) which serve the same purpose described above and shown in Fig. 1 as springs *e*, *f*, advance the bolt so as to correct for play.

Figs. 5 and 6 show variants of interengaging surfaces *h*², and *i*¹, the latter being inclined rather than horizontal as in Fig. 1 and exerting thrust towards or away from the hinges supporting the door, the rest of the assembly remaining the same.

From the foregoing description, it will be seen that whether the bolt structure be of the type shown in Figs. 1 to 3 Fig. 4, the general principle employed is to incline the contacting surfaces of elements *a* and *h* in some direction so that wear may be taken up by springs *e* and *f*.

20 In the claims that follow the word "inclined" is to be interpreted as forming an angle with the plane of the horizon, of the azimuth, or a plane at right angles to the latter.

25 What I claim is:—

1. In a lock, a female element provided with a plane surface inclined relatively to a vertical plane, a male element having a plane surface of like inclination to the inclined surface of said female element, that portion of said male element provided with said inclined surface being, at least in part, of diminishing section, a rigid shell associated with said male element, said shell being positioned so as to frictionally contact with, and rest upon, an exterior portion of said female element, said shell being mounted so that when in contact with said female element, it opposes the thrust produced by contact of the inclined surfaces of said male and female elements, and a spring reacting on said male element and tending to force the latter into said female element.

45 2. In a lock, a female element provided with a plane surface inclined relatively to a vertical plane, a male element having a plane inclined surface of the same inclination as the inclined surface of said female element, that portion of said male element provided with said inclined surface, being, at least in part, of varying section, a spring tending to force the inclined surfaces of said male and female elements into contact with one another, a shell associated with said male element, said shell having a reentrant portion formed thereon and positioned to contact with, and to rest upon, the exterior of said female element, whereby said shell and said inclined surfaces exert opposing forces tending to maintain the lock in the same position regardless of the wear on said male member.

60 3. The lock construction defined in claim 1 in which the male element is provided at its free extremity with a plane surface portion lying substantially in the direction of dis-

placement of the male element relative to the shell.

4. The lock construction defined in claim 1 in which the said inclined surface of the male element terminates in a plane surface portion 70 lying in said vertical plane.

5. The lock construction defined in claim 1 in which the male element is provided at its free extremity with a substantially plane surface portion angularly disposed with respect 75 to said inclined surface of the male element.

In testimony whereof I affix my signature.

ROBERT BIENAIME.
